[57] CLAIM

The ornamental design for a video game controller, as shown and described.

DESCRIPTION

FIG. 1 is a perspective view of a video game controller showing our new design;

FIG. 2 is a top perspective view thereof showing undisclosed sides in FIG. 1;

FIG. 3 is a rear elevational view thereof;

FIG. 4 is a front elevational view thereof;

FIG. 5 is a left side elevational view thereof;

FIG. 6 is a right side elevational view thereof; and,

FIG. 7 is a top plan view thereof.

The bottom surface is plain and unornamented.

The broken line of showing of a conduit in FIGS. 1 and 2 is for illustrative purposes only and forms no part of the claim.
